UNITED STATES PATENT OFFICE.

RICHARD MURR, OF CHICAGO, ILLINOIS.

DESIGN FOR A LAMP-STAND.

No. 38,506.

Specification for Design.

Patented April 2, 1907.

Application filed January 14, 1907. Serial No. 352,309. Term of patent 7 years.

To all whom it may concern:

Be it known that I, RICHARD MURR, a citizen of the United States, residing at Chicago, in the county of Cook and State of Illinois, have invented a new, original, and ornamental Design for Lamp-Stands, of which the following is a specification, reference being had to the accompanying drawing, forming a part thereof.

The figure on the drawing is a perspective view of a lamp-stand, showing my new design.

I claim—

The ornamental design for a lamp-stand, as shown.

RICHARD MURR.
